(57) CLAIM

The ornamental design for a shoe heel, as shown and described.

DESCRIPTION

FIG. 1 is a perspective view of a shoe heel, shown attached to a shoe.

FIG. 2 is another perspective view of the shoe heel of FIG. 1, shown attached to a shoe.

FIG. 3 is another perspective view of the shoe heel of FIG. 1, shown attached to a shoe.

FIG. 4 is a right side elevational view of the shoe heel of FIG. 1, shown attached to a shoe.

FIG. 5 is a left side elevational view of the shoe heel of FIG. 1, shown attached to a shoe.

FIG. 6 is a back elevational view of the shoe heel of FIG. 1, shown attached to a shoe.

FIG. 7 is a top plan view of the shoe heel of FIG. 1, shown attached to a shoe.

FIG. 8 is a bottom plan elevational view of the shoe heel of FIG. 1, shown attached to a shoe.

FIG. 9 is a perspective view of the shoe heel of FIG. 1.

FIG. 10 is another perspective view of the shoe heel of FIG. 1.

FIG. 11 is a back elevational view of the shoe heel of FIG. 1.

FIG. 12 is a front elevational view of the shoe heel of FIG. 1.

FIG. 13 is a left side elevational view of the shoe heel of FIG. 1.

FIG. 14 is a right side elevational view of the shoe heel of FIG. 1.

1 Claim, 14 Drawing Sheets
